LOCKSTITCH SEWING MACHINES

Hans F. Schaefer, Jr., Rockport, and Frank Pulsifer, Hamilton, Mass., assignors to United Shoe Machinery Corporation, Flemington, N. J., a corporation of New Jersey

Application July 5, 1952, Serial No. 297,216

19 Claims. (Cl. 112—38)

The present invention relates to improvements in shoe sewing machines of the type disclosed in an application for United States Letters Patent Serial No. 265,660, filed January 9, 1952, in the name of Alfred S. Clark, in which a shoe upper and a sock lining attached to a rabbeted platform sole and platform wrapper or sole cover strip are sewn together with a lockstitch seam passing through all the parts except the platform sole. In certain of its aspects, the invention is applicable to shoe sewing machines of other types or operations other than those performed upon shoes.

The objects of the invention are to provide a shoe sewing machine of the type referred to, which is simpler, more compact, and more durable in operation, and which may be operated at higher speeds with less effort and attention on the part of the operator and in which the stitch forming devices and other instrumentalities are more readily accessible for manipulation and adjustments, both from a manufacturing as well as an operating standpoint, than heretofore.

A shoe sewing machine of the type referred to is constructed in such manner that the greatest amount of space possible is available about the point of operation of the stitch forming devices consistent with effective design for reliable sewing. In a lockstitch shoe sewing machine a shuttle or loop taker is employed which is located in a position where it will not interfere with proper presentation of a shoe to the machine while sewing about the varying curvatures along the marginal portions of the parts sewn. A common practice is to locate the shuttle directly above or below the sewing point in the machine but spaced a sufficient distance from the sewing point to avoid contact with a shoe being operated upon. When so located, it is necessary to employ a needle loop spreading and lifting device for transferring each loop of thread from the needle to the shuttle. The use of a loop spreader and lifting device adds to the complication of a machine and oftentimes offers further obstacles in the way of proper presentation of a shoe thereto. It is accordingly a further object of the invention to provide a shoe sewing machine with a shuttle or loop taker located so close to the point of needle operation that no loop spreading and lifting device is required without at the same time infringing on the space requirements of a shoe in a manner to handicap its proper presentation to the stitch forming devices of the machine. Still further objects are to simplify and improve the construction of a shuttle or loop taker for this type of sewing machine together with its actuating and driving mechanisms in a manner conducive to high speed operation, convenient maintenance and effective repair.

In accordance with the objects noted, the machine embodying the invention has stitch forming devices including a curved eye-pointed needle oscillating about a supporting stud mounted generally in parallel relation to a main sewing shaft for actuating the devices to form stitches and feed the work, in which the loop taker is constructed with a needle loop entering beak rotating

2

in a plane at an acute angle to that defined by the needle curvature, the plane of the loop taker being intersected by the plane of the needle so that the face of the loop taker is inclined rearwardly away from the needle while the loop taker is mounted at one side of the needle plane as distinguished from a central location directly above or below the needle, as in prior machines. Not only does the location of the loop taker in such angular relation at one side of the needle eliminate the necessity of a loop spreading and lifting device but the driving means for the loop taker shaft is simplified and, in its illustrated form, the loop taker shaft is disposed at an acute angle to the sewing shaft. For convenience in construction and assembly a countershaft is provided with simply formed helical gears connecting the loop taker shaft with the sewing shaft. This arrangement also enables the use of bevel gears on the counter and loop taker shafts for transmitting rotary motion to the loop taker. The angular relation of the loop taker shaft to the sewing shaft, in the described construction, provides a convenient opportunity for mounting a bobbin ejector rod within the loop taker shaft, the end of the rod being exposed for operation at that end of the loop taker shaft opposite the loop taker.

Other features of the invention are embodied in an improved thread case and retainer for preventing rotation of the thread case with the loop taker, in an improved arrangement of actuating and driving mechanisms, and other features of novelty including the devices, combinations and arrangements of parts herein-after described and claimed, the advantages of which will readily be understood from the following detailed specification taken in connection with the accompanying drawings, in which:

Fig. 1 is a view in front elevation, partly broken away and in section, of a shoe sewing machine embodying the features of the present invention;

Fig. 2 is a plan view of the sewing head portion of the machine illustrated in Fig. 1 with parts broken away and shown in section;

Fig. 38 is a sectional view of the loop taker, thread case and assembled bobbin holder;

Fig. 39 is a detail view on an enlarged scale of the operating connections for the bobbin ejector and an interlock mechanism shown in section taken along the line XXXIX—XXXIX of Fig. 1;

Fig. 40 is a detail view of a thread case retainer actuating mechanism showing a thread case retaining pawl disengaged from the bobbin thread holder; and

Fig. 41 is a view of the same parts showing the retaining pawl engaged with the bobbin holder.

The apparatus illustrated in the drawings is a curved eye-pointed needle lockstitch sewing machine adapted to operate upon the marginal portions of a shoe similar to that described in the application above identified and in United States Letters Patent No. 2,546,152, granted March 27, 1951, upon application of J. D. Chandler. The shoe disclosed in the patent is of the platform type in which a sock lining is attached to a rabbeted platform sole above the rabbet and the edges of a precut upper are secured to the sock lining by a seam running along the inner face of the rabbet without including the platform sole. For binding the edge of the platform sole a wrapper or platform cover strip also is attached to the edges of the upper and sock lining, so that the strip may

be lasted over the edges of the parts into overlapping relation with the bottom of the platform sole.

The construction of the shoe is to a large degree determined for its uniformity in contour and appearance upon the manner of guiding and positioning the shoe during the process of inserting the seam attaching the parts together. For producing the best results the parts of the shoe are flexed during the sewing operation to produce the proper shape and the shoe is twisted and turned as the operation progresses to insure that the stitches are inserted with the thread which passes through the material of the parts as close as possible to positions at right angles to the surfaces of the parts at the point of operation. Only by so inserting the stitches will the strain on the stitches, met during subsequent manufacturing operations and wear of the shoe, be resisted effectively, the parts and the shape of the shoe being retained for a maximum period of service.

Proper twisting and turning positioning movements of a shoe during sewing operations is particularly important when operating upon high heeled shoes having abrupt lengthwise curvatures along the edges of their parts, it being necessary to provide sufficient clearances about the operating point of the machine for the shoe in its movements. Sufficient clearances about the operating point in a sewing machine are primarily dependent upon the location and manner of operation of the fundamental stitch forming devices.

The machine of the prior Clark application is provided with a curved eye-pointed needle and a loop taker or shuttle generally similar to the corresponding devices of the present invention. To provide sufficient clearance about the operating point of the Clark machine for proper positioning movements of a shoe, the loop taker or shuttle of that machine is mounted for rotation below the sewing point with its center of rotation approximately in a plane defined by the needle curvature. In order that rotation of the loop taker in the Clark machine will be free of possible interferences by other devices in the machine, the shuttle is spaced below the needle. To engage each loop of thread carried through the work by the needle with the loop taker, the loop is not transferred directly to the loop taker but a loop spreader acts to open each loop and carry it downwardly and rearwardly from the needle into the path of the loop taker beak. By spacing the loop taker in this way, the operating point in the machine is kept free for positioning movements of the shoe. However, with the arrangement of a loop taker mounted to rotate about an axis substantially in the plane of needle curvature beneath the sewing point, it is necessary to obscure access to a supply of locking thread contained therein by the location of a work support in front of the loop taker. It accordingly has been found desirable in the Clark machine to mount the work support on a hinged cover plate so that it may swing outwardly from the loop taker with the cover plate. In this way suitable access to the loop taker for locking thread replacements and adjustments is obtained. Even with maximum effective separation of the loop taker and use of a relatively long stroke, loop spreader to transfer a needle loop to the loop taker in the Clark machine, the space about the sewing point is otherwise restricted and the possible positioning movements of a shoe being sewn are correspondingly limited.

To provide the greatest possible accessibility to the loop taker without restricting the positioning movements of a shoe being sewn in the machine of the present invention, the strict forming devices comprise a hollow discoidal rotary loop taker or shuttle best shown at 2 in Figs. 25 to 38 inclusive having a needle loop entering beak 3 (Fig. 27) mounted for rotation in a plane at an angle to that defined by a curved eye-pointed needle 4. The loop taker is open at its exposed end and provided with a rigid wall at its other end. The needle is secured to a segment 6 rotatably mounted for oscillation on a

stud 8 secured to a carrier 10 (Figs. 5, 6, 21 and 30). The curvature of the needle 4 defines a vertical plane at one side of the circular path through which the beak 3 of the loop taker moves. The beak 3 of the loop taker acts directly on the thread, indicated at 12 in Fig. 30, carried by the needle to open up each loop formed by the needle for passage about an open ended circular locking thread supply case 14 (Figs. 31 and 32) mounted for relative rotation within the loop taker, no separate loop spreader or its actuating mechanism being required. The angular relation of the loop taker plane, indicated at 15 by a dot-dash line, and the plane of the needle enables the thread engaging portions of the loop taker to be located entirely at that side of the needle plane toward which the work moves during sewing operations so that the feed of the work through the machine is not impeded by the action of the loop taker in spreading each needle loop. The planes of the loop taker path and of the needle form an acute angle A (Fig. 26) with its apex line passing approximately through the sewing point or somewhat behind it. In this way a maximum of available space is provided for angular positioning movements of the work during sewing operations.

For mounting and driving the loop taker it is secured to the forward end of a hollow horizontal shaft 16 (Fig. 26), mounted for rotation at an acute angle to the axis of the needle stud 8. The loop taker shaft is driven from a main sewing shaft 18 disposed generally in parallel relation to the needle stud 8 and to the direction of feeding movement of the work through the machine. The loop taker is rotated twice for each single rotation of the sewing shaft.

To connect the loop taker shaft 16 with the sewing shaft 18, in the arrangement of the present invention, the shaft 16 extends rearwardly where it is intersected across its axis by the plane of the needle and near the right end of the sewing shaft beyond the needle plane (Figs. 3 and 4), there is an angle drive between the loop taker and sewing shafts. The angle drive comprises a bevel gear 20 secured to the loop taker shaft, meshing with a corresponding gear 22 of twice the diameter secured on a countershaft 24. The countershaft 24 is disposed at right angles to the sewing shaft 18 and carries a helical gear 26 meshing with a similar gear 28 on the sewing shaft. The countershaft 24 serves both for connecting the sewing and loop taker shafts as well as for transmitting rotary motion from an outside source of power to the loop taker and sewing shafts.

For the purpose of obtaining a compact and simple construction all of the rotary motion, driving power supply members and their connections are mounted and connected to one portion of the sewing shaft at one side of the needle plane extended rearwardly through the frame of the machine and represented at 30 by a dot-dash line (Figs. 3, 4, and 26). At the other side of the needle plane 30 are mounted the actuating mechanisms connected to and driven from another portion of the sewing shaft for imparting reciprocating and oscillating motions thereto. The construction and general arrangement of the machine is accordingly such as will lend itself effectively to the use of a frame comprising an oil retaining housing formed with two compartments, one of which encloses mechanisms for actuating the stitch forming devices and the other of which encloses members of the driving connections for imparting rotary motion to the loop taker and main sewing shafts.

The loop taker is best shown in Figs. 27, 28 and 29 and is constructed in two parts divided along a cordal plane. The loop taker parts are joined together by means of a screw 32 and a pair of dowel pins 34. The main part of the loop taker 2 is the part that is constructed integrally with the shaft 16 and the other part, indicated at 36, is smaller than the main part so that the plane of division between the parts is located at one side of the shaft 16. The smaller part 36 has integrally connected to it, the

beak 3 which extends beyond the plane of division between the parts into overlapping relation with the main part 2, the thread receiving throat of the loop taker being formed in the main part with sufficient depth to enable the needle thread to pass through with proper clearance. For the purpose of entering the needle loop with certainty, the path taken by the loop taker beak is substantially tangent to the plane 30 of the needle. To prevent displacement of the loop from the throat of the loop taker after entering a needle loop, the loop taker part 36 has secured thereto a guard 38 provided with a perforated flange through which passes a clamp screw 40 entering the part 36. The part 36 is recessed to fit the lug of the guard 38 preventing its rotation about the screw 40.

For mounting the thread supply case 14 for relative rotation in the loop taker, the inner surface of the loop taker has a raceway 42 into which fits a radial flange 44 on the thread case. To retain the thread case stationary while the loop taker rotates relatively thereto, the thread case is formed with a projecting right angle tongue 46 which enters a notch in a retainer plate 48, secured to the machine by a pair of screws 50 (see Fig. 40). As each loop of needle thread is engaged with the beak 3 of the loop taker, it is spread and is carried about the locking thread case, one side of the loop entering a cutaway section of the flange 44 on the thread case to be carried to the rear of the thread case while the other side of the loop is carried across the front of the thread case. After passing about the thread case, the loop is drawn upwardly by a take-up 30 and is freed from the thread case, passing between the tongue 46 and the retainer plate 48.

To support a locking thread supply bobbin in the loop taker and to facilitate passage of the thread between the tongue 46 and the plate 48, the thread case has a circular bobbin holder 52 (see Figs. 33, 34, 36 and 37) acting as a readily removable cover for the open end of the thread case and the bobbin holder has a recess 54 toward and from which a cam actuated pawl 56 is moved, shown in Fig. 30. When the pawl moves into the recess 54 the thread case is shifted counterclockwise to a position where the tongue 46 is disengaged from the notched plate 48, the tongue taking up an intermediate position in the notch as illustrated in Fig. 41. This movement of the pawl occurs as the needle loop is being freed from the loop taker so that passage of the needle thread will not be impeded as it is drawn into the work.

For actuating the pawl 56, it is secured to a shaft 58 rotatably mounted at its ends in perforations in a pair of straps 60 fitting grooves at the ends of a block 62, secured to a shouldered surface on the machine frame by a screw 64 (see Figs. 1, 26 and 40). To secure the straps 60 to the block, a pair of screws 66 pass through the straps into threaded engagement with the ends of the block. Connected to the shaft 58 is a yoke-shaped cam follower arm 68, straddling a circular eccentric cam 70 rotatably mounted on the loop taker shaft 16.

The cam 70 is adjustably secured against rotation on the loop taker shaft by a clamp screw 72 passing through an arcuate slot 74 in an end wall of the loop taker and 60 into threaded engagement with the cam (Fig. 27). Loosening the clamp screw 72 allows the cam to be rotated relatively to the loop taker so that the time in which the pawl 56 enters the recess 54 in the thread case bobbin holder may be varied in accordance with requirements.

To enable the beak 3 of the loop taker to support the needle against lateral thrust before the beak of the loop taker enters the needle loop, the main part 2 of the loop taker is formed in advance of the needle loop entering beak with a conical needle engaging surface 76, shown in Fig. 29. This surface extends substantially parallel to the needle while the needle is at the limit of its work penetrating stroke, and not only steadies the needle against thrust resulting from its engagement with the work but also insures that the loop will be engaged properly by the loop taker beak. In forming the conical surface 76, a side

portion and a part of the end wall of the loop taker are cut back so that a side opening is made into the space within the loop taker. For counterbalancing the loop taker so that it may operate at high speeds without excessive vibration the removable part 36 is similarly cut away, the openings formed thereby in the sides of the loop taker providing exits for lint or other foreign materials entering between the loop taker and the thread case. To clear the thread running from the eye of the needle and to prevent abrasive engagement with the conical surface 76, the conical surface on the loop taker is set back to form a step surface 78 located with its step in a position beyond the needle eye, while the point engages the conical surface 76.

To secure the bobbin and holder 52 in place on the thread case the central portion of the holder has a rearwardly projecting hub 80 arranged to enter within a bobbin reel 82 (Fig. 35). To enable the hub 80 on the holder 52 to be brought into alignment with a hub 84 (Fig. 32) on the thread case, both hubs 80 and 84 are provided with central passageways and in the passageway of the holder hub 80 is mounted a shank of a latch 86 which enters a passage 85 in the thread case hub 84 and engages a shoulder formed by the intersection of the passage in the hub 84 and the face of a counterbore in that hub. The latch 86 is formed with an inclined surface which assists in flexing the projecting portion of the latch to impart pressure to it with a component directed toward disengaging position of the latch and with another component directed to resist inward movement of the bobbin thread holder as the rod enters the passage of the hub 84, the latch being of sufficiently resilient material to accommodate such flexing. When the latch 86 engages the shoulder of the hub 84, the holder 52 is retained in covering relation to the thread case 14.

To prevent rotation of the cover and holder 52 on the thread case 14, the holder is formed with a pair of open slots 88 entering radially from the periphery of the thread case, the upper one of which slots receives the base portion of the tongue 46 and the lower one of which receives a lug 90 projecting from the thread case 14 at a position 180° removed from the tongue 46. The holder also carries a bobbin thread tension and quick threading guide eyes so arranged that the bobbin containing the supply of locking thread after being mounted on the hub 80 may have its leading end of thread carried conveniently into proper cooperative relation with the tension and guides in a manner to avoid further manipulation of the thread after the bobbin and holder are applied to the thread case.

The bobbin thread tension comprises a leaf spring 94 extending radially from the hub 80 of the holder cover and terminating flush with the periphery of the holder. The outer end of the leaf spring overlaps a flat surface along one edge of a groove 96 in the radial flange 44, the thread being led from the bobbin through an open thread guide eye 98, between the leaf spring 90 and the flange 96 and through an open sided thread guide eye 100, the opening to which enters the lowermost slot 88. The position of the thread when the supply bobbin 82 is applied to the holder and the holder is threaded, ready for application to the thread case, is best shown in Fig. 35. In this figure the leading end of thread is indicated at 102 and is held temporarily in position while the holder cover is being applied to the thread case. After application of the threaded cover to the thread case the guide eyes 98 and 100 have their side openings closed by engagement with the thread case, the eye 98 being closed by the forward surface on the flange 44 and the eye 100 being closed by the lug 90 which enters the slot 88.

To provide an adjustment for the tension on the bobbin thread, the tension leaf spring 94, which is formed with a perforation fitting the hub 80 of the holder, is engaged between the hub and its outer end by a cam disk 104 also rotatably mounted on the hub 80. To

prevent axial displacement of the cam disk, the hub 80 is grooved to receive a split washer 106 so that it will bear with a uniform pressure against the leaf spring 94. The outer edge of the cam disk 104 has a spiral contour so that as it is turned, it overlaps the leaf spring 94 by different amounts. To increase the tension on the thread, the disk is turned to overlap the leaf spring a greater amount and for less tension by a less amount. To retain the cam disk in adjusted position on the holder, the thread case has a circular series of indentations 103 and the cam disk has a flexible finger 110 which fits into one of the indentations at a time. After application of the thread holder and bobbin to the thread case, the leading end 102 of the bobbin thread is inserted within a guide eye 112 located close to the center of the holder 52.

To enable convenient removal of the bobbin 82 and holder 52 a bobbin ejector is provided, in accordance with one feature of the invention, which is advantageously arranged and simply and effectively operated, at least in part, as a result of the construction of the driving connections for the loop taker. The bobbin ejector comprises a rod 114, best shown in Fig. 26, slidably mounted in line with the latch 86 in a central bore of the loop taker shaft 16. The forward end of the ejector rod has a pointed and tapered terminal arranged to cooperate with the inclined surface of the latch. When the ejector rod is pressed forwardly, it engages the inclined surface of the latch to release it from the shoulder in the hub 84 with one component of movement and to press the latch and holder 52 out of the thread case with another component of movement in the rod. Outward movement of the holder from the thread case carries with it the bobbin so that it may conveniently be removed from the hub on the holder.

For actuating the bobbin ejector the rearward end of the rod 114 is exposed for operation beyond the rearward end of the loop taker shaft 16, opposite the loop taker, and the rod is surrounded by a coil spring 116 compressed between a flanged collar 118 pinned to the ejector rod and a washer 120 engaging the rearward end of the loop taker shaft. Cooperating with the collar 118 is a presser block 122, secured to the lower end of a shaft 124 rotatable in a fixed bearing 125 (see Fig. 39) comprising a boss on a horizontal removable cover 126 for the housing and outside the housing a manually actuated handle 128 is pinned to the shaft (see also Figs. 1 and 2). Rotation of the handle with the shaft brings the block 122 against the collar 118 at the rearward end of the ejector rod to cause the rod to unlatch and remove the bobbin and holder. If the handle 128 is actuated at a time in which the pawl 56 is moved toward the holder 52 into the recess thereof, the force of the ejector rod on the latch 86 may cause breakage or permanent injury to the latch or bobbin holder.

To prevent damage to the latch 86 or the bobbin holder by actuation of the bobbin ejector, while the pawl 56 is moved toward the bobbin holder 52, the ejector is locked from operation when the pawl engages the holder. For this purpose the countershaft 24 has secured to it, between the gears 22 and 26, a cam 130 and the ejector shaft 124 has pinned to it a right angle arm 132, the forward end of which extends in front of the cam 130. Since the bevel gears 20 and 22 are designed to impart two rotations to the loop taker shaft 16 for one of the countershaft 24, the cam 130 is formed with two flat edge surfaces or depressions 134 (Fig. 39) spaced 180° apart, across which the arm 132 may move without interference. When the cam 130 is at any position other than that in which the arm 132 is free to move across a flat surface 134, the handle 128 is locked in inoperative position.

The arrangement of the several interconnected shafts with the two-compartment oil retaining housing, comprising the frame of the machine, is effective in provid-

ing a continually circulating lubricating system for the shafts and a splash lubricating system for the mechanisms for actuating the stitch forming devices. For this purpose one end of each shaft 16, 18 and 24 carrying the bevel and helical gears meshing one with another, all project within a high level oil retaining compartment 138 (Figs. 3 and 4). Also included within the compartment 138 is the rearward end of the bobbin ejector shaft 124. The high level compartment 138 is fed with lubricant through a duct 140, passing through an upper wall of the compartment 138 from a low level oil containing compartment 142. To feed lubricant to the duct 140 the lower end of a conductor 144 is disposed just above it and lubricant flows from its upper end secured in a narrow rectangular casing 146 mounted within the compartment 142. The lubricant is lifted centrifugally into the upper end of the casing 146 by a disk 148 secured to the main sewing shaft 18, the lower edge of the disk 148 dipping below the level of the lubricant in the low level compartment 142. The lubricant carried through the duct 140, first falls upon the counter-shaft carrying gear 26 and is thrown about the space in the compartment 138 to lubricate all of the gears and shafts, the surplus lubricant running through the shaft bearings and back into the low level compartment. To prevent the level of the lubricant in the high level driving connection compartment from reaching the sewing shaft so that it may carry sludge or foreign materials into the sewing shaft bearings, the two compartments are connected by an overflow passageway 150 (Fig. 15), above the level of the lubricant in the low level compartment 142.

To provide access to the compartments 138 and 142, the cover plate 126 is secured in place by screws 152; and the low level compartment is enclosed by a separable wall member 154, retained in position by a thumbscrew 156 (Figs. 2 and 25) passing through an opening in the wall member and into a threaded block 158 on the machine frame. The upper portion of the low level compartment 142 has formed in it between the stationary housing frame and the separable wall member 154, an opening 160 (see Figs. 4 and 25) through which projects a main take-up for controlling the thread requirements of the other stitch forming devices, for setting each stitch and for pulling off a supply of needle thread for each successive stitch from a thread tension. The exposed end of the take-up, indicated at 162, is enclosed by a cover 164, hinged by a stud 166 to a block 168 and secured to the housing frame by a screw 170 (Figs. 4 and 17). For retaining the cover in position, it carries a spring pressed plunger 171 engaging a recess in the block 168 while the cover is in closed position. The take-up is particularly well fitted for the purposes intended and is arranged with fixed and movable thread guides in a manner to supplement the effectiveness of the thread tension in imparting a uniform tension to the thread reliably throughout a large range of variable conditions met in operating upon different qualities of work.

Referring to Figs. 4, 15 and 17, the take-up 162 comprises a lightweight alloy arm having suitable weight-reducing lengthwise slots 172 and connecting struts with a friction-reducing pulley 174, mounted at its upper end. Beneath the pulley 174 on the arm of the take-up 162 is a friction-producing thread eye 176. Cooperating with the pulley 174 and the eye 176 are a relatively fixed friction-reducing pulley 178 and a friction-producing eye 180 formed in a plate 182 adjustably secured to a bracket 184 on the housing frame. The needle thread 12 is drawn from a suitable supply (not shown) through a preliminary tension guide bar 186 on the housing frame and past the tension which is of conventional construction including a pair of thread engaging disks 188 and 190, slidably supported on a central spindle 192, clamped to a thimble 193 comprising the tension. The thimble is removably secured within an open-

ing in the housing frame. Also clamped within the thimble 193 is one end of a torsion spring 194 having its free end formed into an eye to impart an auxiliary yielding tension to the thread after leaving the tension disks 188 and 190. As shown in Fig. 18 the tension disks are pressed yieldingly together by a spring 196 acting between the disk 188 and a washer 198 held in place by a thumbscrew 200 threaded on the upper end of the spindle 192.

From the auxiliary tension spring 194 the thread 12 passes through a lubricator consisting of a perforated wick contained in a tube 202 mounted in a cover 204 at the upper end of a cylindrical reservoir 206. From the thread lubricator tube 202, the thread passes through the fixed friction thread eye 180 to the movable friction thread eye 176 in the take-up 162, the fixed friction-reducing pulley 178, the movable friction-reducing pulley 174, a thread guide eye 208 in the housing frame, and to the eye of the needle 4. As in the machine of the Clark application, the thread also passes through an eye in a needle guide 210 operating in a manner similar to that described in that application.

The use of the friction-producing guide eyes 176 and 180 and the friction-reducing pulleys 174 and 178, mounted upon or cooperating with the take-up 162, are of advantage where different qualities are met in the material of the work operated upon. The pulley 178 is located outside the range of movement of the take-up, so that control of the thread is provided sufficient for the requirements of the stitch forming devices, except for the application of a final tension in setting each stitch, and in drawing a supply of thread past the tension disks 188 and 190. Within the range of take-up movement and nearer to the limit of its movement at which each stitch is set, the friction-producing guide eyes 176 and 180 come into operation, the friction eyes having little or no effect on the take-up action throughout the remainder of the take-up movement.

Variations in resistance met in drawing the sewing threads into final position in the work, as a result of differences in the resiliency and frictional characteristics of the work, are somewhat compensated for through the action of the friction eyes. The frictional action of the thread in the eyes also tends to delay the sliding movement of the thread through them with hard thick work. In this way the stitches are set more deeply in hard thick work which has less resiliency than with softer or more resilient thinner work. The action of the friction eyes 176 and 180 is effective in drawing the thread into final position only at the stitch setting limit of take-up movement, because the two eyes are located to bring them into alignment in a position between the limits of take-up movement and closer to the stitch setting end of that movement. Before the aligned position of the eyes is reached, the friction on the thread produced by the eye 176 is negligible, since the total tension on the thread is relatively low and the frictional forces on the thread as it passes the eye 176 are those resulting from pressures of the thread at diametrically opposite edges of the eye, there being substantially no movement of the thread through the eye 180. As the eye 176 moves past a position of alignment with the eye 180 towards a stitch setting position, a much greater tension is applied to the thread and the thread bears against one side only of the eye 176 throughout the length of the eye. As the limit of stitch setting movement of the take-up 162 is reached, the thread is drawn through the fixed eye 180 from the tension disks and from the stitch being set in the work through the movable eye 176, tending to cause a still greater tension on the thread running between the eyes than upon that portion of thread running to the stitch being set. Greater tension on the thread between the thread eyes than on the thread running to the stitch being set is of advantage because it causes stitches to be set with greater tension in hard thick work than with soft thin

work. With thin work there is no movement of the thread through the eye 176 after setting each stitch, the direct action of the take-up and the fixed eye 180 pulling off sufficient thread for each stitch from the tension disks. With greater thickness or lack of pliability in the work more thread is required than can be pulled off from the tension disks without slippage in the eye 176. The stitch setting tension in the thread running to the stitch in the work, therefore, must increase to a point where it overcomes both the frictional action imparted to the thread passing through the eye 176 and that imparted to the thread passing through the fixed eye 180, so that the tension on the thread between the eye 176 and the stitch being set is greater than that applied by the tension disks. Therefore, it is more than likely with thick, hard work that the stitches will be set more securely to hold the parts together against the increased resistance offered than with thin, more pliable work.

As a means to adjust the action of the stitch setting take-up when the machine is first assembled and to offset the elasticity of the thread when thread of different quality is employed, a convenient adjustment is provided in the illustrated take-up structure. For these purposes the position of the fixed eye 180 may be shifted relatively to the stitch setting limit of take-up movement. To adjust the eye 180 the plate 182 is slotted and has passing through it a clamp screw 212 entering a threaded opening in the bracket 184. By loosening the clamp screw 212 the portion of take-up movement through which both friction producing guide eyes are effective in taking up thread may be increased or decreased in the desired manner.

Since the construction of the take-up has been designed to provide the greatest strength for the lightest possible weight, it is desirable to protect the operating end of the take-up 162 from possible danger of injury or contact with the operator's hands at all times during the operation of the machine. To insure closing the cover 164 before starting the machine, the pulley 178 is mounted on the cover, it being necessary to move the cover to closed position in order to bring the pulley 178 into proper sewing relationship with the take-up. By mounting the guide pulley 178 on the take-up cover, greater freedom also is obtained in threading both the fixed and movable guides and there is less likelihood of improper threading. Accordingly, the added protection of the cover with a guide pulley mounted thereon renders the machine inoperative without protecting the take-up.

In order to observe the action of the thread passing through the fixed and movable guide eyes and pulleys while the take-up cover is closed and after adjustments are made in the fixed guide eye 180, the take-up cover 164 has a transparent window 214, shown in Figs. 1 and 25, comprising a sheet of plastic material attached by screws 216 to the cover 164.

The use of a two-compartment oil retaining housing is of advantage, not only in maintaining different levels of lubricant between the two compartments but also because the lubricant requirements for oscillating and reciprocating parts in the mechanisms for actuating the stitch forming and work feeding devices are different from those for continuously rotating gears and shafts with their bearings. It is recognized that for oscillating and reciprocating parts a light air supported spray is preferable, whereas with continuously rotating parts a solid stream of lubricant is more effective. For providing a solid stream of lubricant to the connecting gears and shafts of the present machine, the casing 146 (Fig. 15), to which the conductor 144 is attached, is mounted upon a projecting lug 217 of the machine frame by a pair of cap screws 218 passing through a flange at one side of the casing. The flange on the casing also surrounds a substantial proportion of the periphery of the disk 148 so that the lubricant entrained by the disk is carried with certainty in the direction of the arrows 219 into the upper end of the casing to the location of the conductor inlet. The casing

also has attached to it a shield portion 220 (see Fig. 4) extending over other rotating parts of the actuating mechanisms close to the entraining disk 148.

All of the mechanisms for actuating the stitch forming and feeding devices with the exception of the loop taker, which is continually rotated and the take-up which is cam actuated, are driven from crank actuated mechanisms located at the right side of the needle plane 30 in Fig. 4. The take-up mechanism is relatively simple and comprises a lever 221, to an upwardly extending arm of which the take-up 162 is made fast. The lever 221 is mounted for oscillation on a stud 222 (Fig. 15) secured at its ends in the machine frame. On a horizontal arm of the lever 221 is a roll 224 engaging a cam slot cut in the disk 148.

The needle actuating mechanism is illustrated in Figs. 3, 4, 5, 9 and 21 to 24 inclusive. This mechanism is driven from a counterbalanced crank 226 on the main sewing shaft 18. The crank 226 is surrounded by one end of a pitman 228 having a downwardly extending finger 230 arranged to dip below the surface of lubricant in the compartment 142 and produce a spray lubrication for the mechanisms in that compartment. Connected to the other end of the pitman by a pivot 231 is one arm of a lever 232 fulcrumed on a stud 234 (see Fig. 7), mounted in a depending arm of a bracket 236 fixed to a bracket 237 which supports the feed carrier frame 10. The lever 232 has a horizontal arm, within a slot in which is slidably mounted a rectangular perforated block 238 surrounding a dowel projecting from one arm of a lever 240 (see Fig. 5). The lever 240 oscillates on a stud 242, secured in a swinging frame comprising the work feed carrier 10, the carrier being generally similar to that described in the Clark application above identified. Connected to the rearward end of the lever 240 by a pin 244 (Fig. 21) is one end of a needle segment actuating link 246, the other end of which is pivotally connected to the segment 6 by a pin 248. The link 246 also has pivoted to it at 250 a needle guide actuating link 252. The lower end of the link 252 is pivotally connected to a rearwardly projecting lug 254 (Fig. 21) on the needle guide 210, which needle guide is in the form of a lever mounted for oscillation on the needle stud 8. The needle itself is secured in a clamp formed in part by an arcuate recess in the needle segment and in part by an arcuate wedge block forming the head of a clamp bolt 256 passing through the needle segment.

The illustrated machine is provided with a work support and work clamping and feeding devices generally similar to the corresponding devices disclosed in the Clark application. The work support is shiftable during sewing to accommodate varying thicknesses of work resulting in the use of a platform sole having a heel portion integral with the forepart and of substantially greater thickness than the forepart. The work clamping and feeding devices comprise a primary stationary or non-feeding work clamp and a supplementary work feeding clamp having cooperating members consisting, in each case, of a presser foot and a gage arranged for entry into the rabbet of the platform sole operated upon to guide the location of the seam inserted.

The present work support consists of a horizontal plate 258 mounted just below the operating point of the stitch forming devices and best shown in Figs. 21 and 25. In order that the work support plate may be effective in use where a platform sole, having less thickness along the forepart and greater thickness along the heel portion, is being operated upon, a mounting for the plate is provided which is quickly shiftable to either of two fixed vertically spaced positions. For this purpose the plate 258 has a vertical shank sliding in a dove-tail groove of a slotted block 260, forming a guideway for the work support. The block 260 is, in turn, adjustable on the machine frame and is arranged with a vertical

tongue and groove connection to a fixed bracket 261. To maintain the block 260 in fixed relation vertically on the bracket 261, the slot in the block has passing through it a clamp screw 262.

The two positions of the work support are adjustable in their spacing. Releasing the clamp screw 262 enables the work support and its mounting to be shifted adjustably to an upper position where any thickness of a relatively thin platform sole forepart may be operated upon effectively. To adjust the lowermost position of the work support for convenient operation of the machine on a relatively thick heel portion, the block 260 has threaded into a vertical passage therein, a setscrew 263 arranged at its upper end in close proximity to the under surface of the work support plate 258. To retain the work support against the setscrew 263, there is stretched a tension spring 268 between a pin on the shank of the work support and a pin on the block 260. For raising the work support plate from its lowermost position to its uppermost position against the force of the spring 268, a shoulder on the shank of the work support is engaged with a flipper 265 having a cam surface 267 against which the shoulder rests. The flipper is rotatably mounted on a shoulder screw 270 passing through a slot in the shank of the work support and into threaded engagement with the block 260. The flipper is provided with a handle portion by which it may be rotated to raise and lower the work support, the cam surface on the flipper being so shaped as to cause the work support to be retained frictionally in raised position, shown in Fig. 25.

The machine is provided with an adjustable edge gage 271 (Fig. 21) for guiding the line of the seam inserted. The edge gage is secured to a vertical arm 272 rotatably mounted on a horizontal hinge pin 273, carried by the bracket 261. To adjust the edge gage the rearward surface of the arm 272 is engaged by a cam surface on a manually rotatable arm 274, rotatable on a screw stud 275, threaded into the bracket 261. To hold the adjusting arm 274 in adjusted position, the stud 275 carries a leaf spring 276 attached to the arm 272 by a screw which bears against fixed bracket 261 and is located between the arm and the bracket to impart a frictional resistance to free rotation of the arm 274.

As best shown in Figs. 5, 6, 7 and 11, the work feeding clamp comprises a presser foot 277 and a rabbet gage 278 between which a sock lining, an upper and a platform cover of a shoe are clamped and fed. The rabbet gage 278 is secured in place with a rib and groove joint by a clamp screw 279 passing through the shank of the gage into a forwardly projecting portion of an open frame comprising the carrier 10. The work feeding foot 277 is secured with a rib and groove joint by a clamp screw 281 to a feed foot lever 282 rotatable about a stud 283 passing through a forked end of the lever and a frame portion of the feed carrier 10 which is surrounded by the forked end of the lever. The work feeding rabbet gage and presser foot being mounted on the carrier 10 along with the needle, act with the needle to feed the work so that a positive spacing movement is imparted to the work.

The supplementary non-feeding work clamp, shown in Figs. 10, 11 and 12, comprises a presser foot 284 and a rabbet gage 285 for clamping the sock lining, upper and platform cover of the shoe. The rabbet gage 285 is secured with a rib and groove joint by a clamp screw 286 (Fig. 25) to a lug on the machine frame, the clamp screw 286 passing through the shank of the gage 285 into the lug. The presser foot 284 is mounted in a manner similar to that of the presser foot 277, with a rib and groove joint by a clamp screw 287 threaded into a fork ended presser foot mounting lever 288. The presser foot mounting lever 288 has passing through its forked end a stud 289 and is rotatable with the stud. The stud is mount-

ed in bearings in the bracket 236, the studs 283 and 289 being in substantial alinement.

For actuating the work feeding presser foot 277 to clamp and release the work in timed relation to the work penetrating movements of the needle, the rearward end of the needle actuating link 246 carries a pivot pin 292 passing also through the lower end of a link 293, the upper end of which is pivotally connected at 294 to a floating presser foot actuating lever 295. The presser foot actuating lever 295 is fulcrumed on the presser foot mounting lever 282 by a bolt 296 passing through the actuating lever 295 and the mounting lever 282. A third point of connection for the lever 295 comprises a downwardly extending arm having a ball head 297 surrounded by a spherical socket in a link 298 (see Figs. 10, 11, 12 and 14). The link 298 has a second spherical socket surrounding a ball headed pin 299 secured in the non-feeding supplementary presser foot mounting lever 288. The arrangement of the pivotal connections with the lever 295 causes it to impart alternate work clamping and presser foot lifting motions to the work feeding and non-feeding levers 282 and 288.

To maintain a uniform pressure of the presser feet against the work supported by the work table and rabbet gages, a yielding force is exerted on a forked portion of the non-feeding presser foot mounting lever 288, through the fork of which passes the forward end of a rod 300 surrounded by a compression spring 302. The compression spring 302 acts at its forward end upon a sleeve 304, sliding on the rod 300 and at its rearward end on an enlarged head on the rod. The upper end of the rod is recessed to receive the rounded end of a setscrew 306 (Fig. 10) threaded in a plate 308 fixedly mounted inside the frame of the compartment 142. The arrangement is such that the force of the spring 302 is exerted directly by the collar 304 on the non-feeding foot 284, while in engagement with the work and through the link 298 to the lever 295 while the feeding foot engages the work, the application of pressure being alternately transferred from one foot to the other during the clamping and releasing action of the respective presser feet. The ball-and-socket connections with the link 298 permit the feeding foot 277 to move in the direction of feeding movement with relation to the non-feeding foot 284 and the block-and-slot connection between the levers 240 and 232 enables a portion of the presser foot actuating mechanism to oscillate the feeding foot as the feed carrier 10 moves to feed the work without interference with the work clamping action.

The frame of the feed carrier 10 is constructed with a C-shaped design and oscillates about a pair of alined vertical spindles 318 (see Fig. 5), clamped within lugs formed on the bracket 237, between which lugs the carrier is disposed. To oscillate it the carrier also has an arm projecting toward the left from the needle plane 30, to which arm is clamped a ball headed bolt 319. The head of the bolt 319 (Fig. 6) is surrounded by a socket in the forward end of a link 320 forming a part of the work feed mechanism which actuates the work feed carrier through a short angular movement about the vertical spindles 318.

The work feed mechanism includes the link 320 and is adjustable during sewing operations to vary the length of the stitches inserted by the machine. For this purpose the rearward end of the link 320 has a spherical socket surrounding a ball head on a bolt 321 passing loosely through one end of a link 322. The links 320 and 322 comprise a toggle, the central joint of which is formed by the bolt 321. The bolt 321 is actuated vertically to impart a feeding movement to the feed carrier by mechanism shown in Fig. 9. For actuating the bolt 321 it is secured at its end opposite its ball head in the lower end of a pitman 323, carried by a crank pin 324 projecting from a crank arm 325. The crank arm 325 is keyed to the crank 226 in a position where there is

less eccentricity in the crank pin 324 than in the crank 226. Vertical movement of the bolt 321 causes more or less work feeding movement to be imparted to the carrier 10 determined upon the position of the toggle link 322.

To adjust the amount of feeding movement imparted to the carrier 10 and to the work being operated upon, the end of the toggle link 322 opposite the bolt 321 is pivotally mounted on a pin 326 (Fig. 8) passing through the forked ends of a feed adjusting arm 327. The arm 327 is secured to a shaft 328 rotatable in a fixed bearing in the machine frame for movement toward and from a position where the pin 326 comes into alignment with the bolt 319. When the aligned position is reached, no feeding movement is imparted to the carrier through vertical movement of the central joint between the toggle links.

To enable the feeding movement to be adjusted by a conveniently located treadle connection, the adjusting arm 327 has secured in it a pin to which one end of a tension spring 329 is attached, the other end of which is similarly attached to a pin in the frame of the machine (Fig. 8). The spring 329 maintains the adjusting arm in a position with a maximum feeding movement in the carrier 10. To reduce the feeding movement in the carrier 10, the shaft 328 has secured to it outside the machine frame an arm 330 pivotally connected to a treadle rod 331. Downward movement of the treadle rod swings the adjusting arm to bring the pin 326 and the bolt 319 more closely toward an aligned position. To determine the limits of adjusting movement in the arm 327, the arm carries a pair of set screws 332, cooperating with a shoulder 333 on a fixed part of the machine frame.

The countershaft 24 is rotatably mounted within a readily removable flanged mounting sleeve 334 (Fig. 1), secured in an opening through the side wall of the high level oil retaining compartment 142 against axial movement. For this purpose, the flange of the sleeve has passing through it a number of clamp screws 335 threaded in the side wall of the high level compartment 142. Removal of the clamp screws enables the countershaft and sleeve to be withdrawn endwise as a unit from the machine through a driving compartment 336, from which the outer end of the countershaft projects. The outer end of the countershaft has secured thereto a driving pulley 337 within the compartment 336 and a hand wheel 338 outside the compartment.

To provide clearance for the pulley 337 and the sleeve 334, the opening in the driving compartment through which the countershaft projects is of a greater diameter than the pulley and sleeve and is closed by a centrally perforated disk 339 surrounding the countershaft and retained frictionally within the opening of the countershaft compartment wall. After the removal of the countershaft, the loop taker shaft may readily be removed from the machine.

For providing means to enable convenient removal of the loop taker shaft it is rotatably mounted in bearings supported in part by a bearing sleeve 340 (see Fig. 26) entering a close fitting passage in the machine frame. One of the bearings, indicated at 341, is of the end thrust type and is secured in the sleeve and on the looptaker shaft. To secure the loop taker bearing sleeve in place, the sleeve is engaged by a clamp screw 342 having a reduced section midway between its ends through which the side of the bearing sleeve passes. The clamp screw has at its outer end a nut 344 which, when tightened, draws an increasing diameter portion of its inner end tightly against the bearing sleeve to hold it in place. With this arrangement, assembly and disassembly of the machine is facilitated and adjustments of the mechanisms inside the housing of the machine are conveniently made.

In order to release the work from the machine at the end of a seam, both the feeding and non-feeding presser feet are raised from engagement with the work through

the action of a single treadle actuated connection. The treadle actuated connection for raising the presser feet comprises a lever 346, fulcrumed on the stud 289 (see Fig. 10) and is formed at one end with a rounded surface 5 to engage the underside of the non-feeding presser foot lever 288. The other end of the presser foot raising lever 346 is pivotally connected by a pin 348 to an angle link 350, connected in turn by a pin 352 (Fig. 15) to an arm 354 secured to a horizontal shaft 356 rotatable in the 10 machine frame with one end projecting into a control compartment 357 (Fig. 2). Also secured to the shaft 356, inside the control compartment, is an arm 358 (Fig. 1) having its free end pivotally connected with a treadle rod 360. When the treadle rod is depressed, the presser 15 foot raising lever 346 engages the lever 288 acting directly to disengage the non-feeding foot from the work. Raising movement of the non-feeding foot acts through the link connection 298 to raise also the feeding foot.

In raising the presser feet from engagement with the 20 work the tension on the sewing thread is released so that work may readily be withdrawn from the machine without severing the thread. For this purpose, the spindle 192 of the thread tension has a concentric bore in which is disposed the stem of a T-shaped bar 362 as shown in Figs. 18, 19 and 20. The cross portions of the bar 362 project through a diametric slot in the spindle to engage the uppermost tension disk 188 within a counterbore thereof. The lower end of the bar 362 projects beyond the lower end of the spindle 192 and is disposed in the 25 path of movement of a horizontal arm on a tension release lever 364 (see Figs. 15 and 16). The lever 364 is rotatable on a shoulder screw 366 passing through the lever and into a portion of the machine frame. A downwardly extending arm on the tension release lever is 30 formed with a cam surface arranged to be engaged with the side of the angular link 350 as the presser feet are being disengaged from the work.

Certain features of the invention herein disclosed form 35 the subject-matter of divisional applications, as follows: Serial No. 514,576, filed June 10, 1955, relating to driving and lubricating devices for sewing machines; and Serial No. 574,813, filed March 29, 1956, relating to an improved take-up for sewing machines.

The nature and scope of the invention having been indicated and an embodiment having been described, what is claimed is:

1. A shoe sewing machine having stitch forming and work feeding devices including a curved, eye-pointed needle, a stud about which the needle oscillates, and a main sewing shaft for actuating the stitch forming and work feeding devices arranged generally in parallel relation to the needle stud, in combination with a rotary loop taker having a needle loop entering beak mounted for rotation in a plane at an acute angle to that defined by the needle and a shaft on which the loop taker is mounted intersected across its axis by the plane of the needle.
2. A shoe sewing machine having stitch forming and work feeding devices including a curved, eye-pointed needle, a stud about which the needle oscillates, and a main sewing shaft for actuating the stitch forming and work feeding devices arranged generally in parallel relation to the needle stud, in combination with a shaft intersected across its axis by the plane of the needle, and a rotary loop taker on the shaft having a needle loop entering beak mounted for rotation in a circular path within a plane disposed at an acute angle to that defined by the needle and at position with relation to the needle in which the plane of the needle is substantially tangent to the circular path of the loop taker beak.
3. A shoe sewing machine having stitch forming and work feeding devices including a curved, eye-pointed needle, a stud about which the needle oscillates, and a main sewing shaft for actuating the stitch forming and work feeding devices arranged generally in parallel relation to the needle stud, in combination with a rotary loop taker

having a needle loop entering beak mounted for rotation in a plane at an angle to that defined by the needle, a holder for supporting a bobbin in the loop taker, a shaft on which the loop taker is mounted intersected by the plane of the needle, an angle drive between the loop taker and the sewing shafts at one end of the sewing shaft comprising bevel gears on the loop taker and sewing shafts and a bobbin ejector comprising a rod slideable in the loop taker shaft and exposed for operation beyond that end of the loop taker shaft opposite the loop taker.

4. A shoe sewing machine having stitch forming and work feeding devices including a needle, a loop taker provided with a needle loop entering beak, a thread case mounted for relative rotation within the loop taker, a thread case retainer for preventing relative rotation of the thread case with the loop taker, a holder for supporting a bobbin removably mounted on the thread case, a latch on the holder engaging the thread case for securing the bobbin against displacement, and a hollow shaft at one end of which the loop taker is mounted, in combination with a bobbin ejector comprising a rod slideable in the loop taker shaft and mounted in line with the latch on the bobbin holder to release the latch from the holder and to press the holder out of said thread case.

5. A shoe sewing machine having stitch forming and work feeding devices including a needle, a loop taker provided with a needle loop entering beak, a thread case mounted for relative rotation within the loop taker, a thread case retainer for preventing relative rotation of the thread case with the loop taker, a holder for supporting a bobbin removably mounted on the thread case, a latch on the holder engaging the thread case for securing the bobbin against displacement, and a hollow shaft at one end of which the loop taker is mounted, in combination with a bobbin ejector comprising a rod slideable in the loop taker shaft and mounted in line with the latch on the bobbin holder to release the latch from the holder and to press the holder out of said thread case, said rod having a tapered terminal and said latch having an inclined surface cooperating with the terminal on the rod to impart pressure to the latch with one component directed toward disengaging position and with another component directed toward removal movement of the thread holder.

6. A shoe sewing machine having a shaft, stitch forming devices driven from the shaft including a needle, a loop taker provided with a needle loop entering beak, a thread case mounted for relative rotation within the loop taker, a thread case retainer comprising a tongue on the thread case and a fixed notched member engaged by the tongue on the thread case for preventing rotation of the thread case with the loop taker, a holder for supporting a bobbin removably mounted in the thread case, means for disengaging the tongue from the notched member as each loop of needle thread is passing between said tongue and member including a pawl and mechanism for actuating the pawl intermittently toward and from the holder, and a bobbin ejector for pressing the holder out of the thread case, in combination with means carried by the countershaft for locking the ejector to prevent its movement into operative position except when the pawl is moved away from the holder.

7. A shoe sewing machine having a shaft, stitch forming devices driven from the shaft including a needle, a loop taker provided with a needle loop entering beak, a thread case mounted for relative rotation within the loop taker, a thread case retainer comprising a tongue on the thread case and a fixed notched member engaged by the tongue on the thread case for preventing rotation of the thread case with the loop taker, a holder for supporting a bobbin removably mounted in the thread case, means for disengaging the tongue from the notched member as each loop of needle thread is passing between said tongue and member including a pawl and mechanism for actuating the pawl intermittently toward and from the holder,

and a bobbin ejector for pressing the holder out of the thread case, in combination with means carried by the countershaft for locking the ejector to prevent its movement into operative position except when the pawl is moved away from the holder, said locking means comprising a cam on the shaft, and an arm secured to the bobbin ejector cooperating with the cam.

8. A shoe sewing machine having a countershaft, stitch forming devices driven from the countershaft including a needle, a rotary loop taker provided with a needle loop entering beak and a thread case mounted for relative rotation with the loop taker, a shaft to which the loop taker is secured, geared driving connections between the countershaft and the loop taker shaft for rotating the loop taker shaft twice for each single rotation of the countershaft, a thread case retainer comprising a tongue on the thread case and a fixed notched member engaged by the tongue on the thread case for preventing rotation of the thread case with the loop taker, a holder for supporting a bobbin removably mounted on the thread case, means for disengaging the tongue from the notched member as a loop of needle thread is passing between said tongue and member including a pawl and a cam on the loop taker shaft for actuating the pawl intermittently toward and from the holder, and a bobbin ejector for pressing the holder out of the thread case, in combination with means carried by the countershaft for locking the ejector to prevent its movement into operative position except when the pawl is moved away from the holder, said locking means comprising a cam on the countershaft having two spaced depressions, and an arm secured to the ejector cooperating with the cam to enable actuation of the bobbin ejector in either of two positions of the cam.

9. A shoe sewing machine having a countershaft, stitch forming devices driven from the countershaft including a needle, a loop taker provided with a needle loop entering beak, a shaft to which the loop taker is secured, a thread case mounted for relative rotation with the loop taker, and means for preventing rotation of the thread case with the loop taker comprising a pawl and a cam on the loop taker shaft for actuating the pawl intermittently away from the thread case as each needle loop is being carried about the thread case by the loop taker, in combination with a clamp screw and arcuate slot connection between the cam and the loop taker for adjustably securing the cam against rotation on the loop taker shaft.

10. A shoe sewing machine having a countershaft, stitch forming devices driven from the countershaft including a needle, a discoidal loop taker provided with a needle loop entering beak and a rigid end wall having an arcuate slot therein, a shaft to which the loop taker is secured, a thread case mounted for relative rotation with the loop taker, and means for preventing rotation of the thread case with the loop taker comprising a pawl and a cam rotatably mounted on the loop taker shaft for actuating the pawl intermittently away from the thread case as each needle loop is being carried about the thread case by the loop taker, in combination with a clamp screw passing through the arcuate slot in the end wall of the loop taker and into the cam for securing the cam adjustably against rotation on the loop taker shaft.

11. A shoe sewing machine having stitch forming devices including a curved eye-pointed needle, a stud about which the needle oscillates and a main sewing shaft for actuating the stitch forming devices, in combination with a rotary loop taker mounted for rotation at one side of a plane defined by the needle, and a shaft to which the loop taker is secured mounted for rotation at an acute angle to the axis of the needle stud and intersected by the plane of the needle, said loop taker being formed with a conical needle engaging surface located in advance of the needle loop entering beak to support the needle against lateral thrust before the beak enters each needle loop.

12. A shoe sewing machine having stitch forming devices including a curved eye-pointed needle, a stud about

which the needle oscillates and a main sewing shaft for actuating the stitch forming devices, in combination with a rotary loop taker mounted for rotation at one side of a plane defined by the needle, and a shaft to which the loop taker is secured mounted for rotation at an acute angle to the axis of the needle stud and intersected by the plane of the needle, said loop taker being formed with a conical needle engaging surface located in advance of the needle loop entering beak to support the needle against lateral thrust before the beak enters each needle loop, the loop taker beak being shaped with a surface extending substantially parallel to the needle while the needle is at the limit of its work penetrating stroke.

13. A shoe sewing machine having stitch forming devices including a curved eye-pointed needle, a stud about which the needle oscillates and a main sewing shaft for actuating the stitch forming devices, in combination with a rotary loop taker mounted for rotation at one side of a plane defined by the needle, and a shaft to which the loop taker is secured mounted for rotation at an acute angle to the axis of the needle stud and intersected by the plane of the needle, said loop taker being formed with a conical needle engaging surface located in advance of the needle loop entering beak to support the needle against lateral thrust before the beak enters each needle loop and being constructed in two parts divided along a cordal plane with the loop entering beak projecting from one of the parts beyond the plane of division between the parts and into overlapping relation with the other part.

14. A shoe sewing machine having stitch forming devices including a curved eye-pointed needle, a stud about which the needle oscillates and a main sewing shaft for actuating the stitch forming devices, in combination with a rotary loop taker having a needle loop entering beak mounted for rotation at one side of a plane defined by the needle, and a shaft to which the loop taker is secured mounted for rotation at an acute angle to the axis of the needle stud and intersected by the plane of the needle, said loop taker being formed with a conical needle engaging surface located in advance of the needle loop entering beak to support the needle against lateral thrust before the beak enters each needle loop and with a setback step surface along that portion of the conical surface past which the point of the needle first moves to clear the thread running from the needle eye from engagement with the conical surface.

15. A shoe sewing machine having stitch forming and work feeding devices including a curved eye-pointed needle, a loop taker provided with a needle loop entering beak, a shaft to which the loop taker is secured and an open ended thread case mounted in the loop taker for rotation relative thereto and provided with a cover positioning lug, in combination with a bobbin holder acting as a readily removable cover for the open end of the thread case and having a bobbin entering hub and a slot to receive the lug on the thread case for maintaining the holder in predetermined angular position on the thread case.

16. A shoe sewing machine having stitch forming and work feeding devices including a curved eye-pointed needle, a loop taker provided with a needle loop entering beak, a shaft to which the loop taker is secured and an open ended circular thread case mounted in the loop taker for rotation relative thereto and provided with a cover positioning lug, in combination with a bobbin holder acting as a readily removable cover for the open end of the thread case and having a radial slot to receive the lug on the thread case for maintaining the holder in predetermined angular position on the thread case, and bobbin thread guides including an eye in the bobbin holder opening into the slot for easy threading and arranged

to be closed by the lug on the thread case when the holder is covering the open thread case end.

17. A shoe sewing machine having stitch forming and work feeding devices including a curved eye-pointed needle and a loop taker provided with a needle loop entering beak, a shaft to which the loop taker is secured, an open ended thread case mounted for rotation relative to the loop taker and provided with a cover positioning lug, in combination with a circular bobbin holder acting as a cover for the open end of the thread case and having a radial flange provided with thread guide eyes and a slot to receive the lug on the thread case for maintaining the holder in predetermined angular position on the thread case, and a bobbin thread tension on the holder comprising a leaf spring secured to the central portion of the holder with its free end projecting radially therefrom between said guide eyes.

18. A shoe sewing machine having stitch forming and work feeding devices including a curved eye-pointed needle and a loop taker provided with a needle loop entering beak, a shaft to which the loop taker is secured, an open ended thread case mounted for rotation relative to the loop taker and provided with a cover positioning lug, in combination with a circular bobbin holder acting as a cover for the open end of the thread case and having a radial flange provided with thread guide eyes and a slot to receive the lug on the thread case for maintaining the holder in predetermined angular position on the thread case, and a bobbin thread tension on the holder comprising a leaf spring secured to the central portion of the holder with its free end projecting radially therefrom between said guide eyes, said eyes being formed with side openings to enable lateral threading arranged to be closed through contact with the thread case.

19. A shoe sewing machine having stitch forming and work feeding devices including a curved eye-pointed needle and a loop taker provided with a needle loop entering beak, a shaft to which the loop taker is secured, an open ended thread case mounted for rotation relative to the loop taker and provided with a cover positioning lug, in combination with a circular bobbin holder acting as a cover for the open end of the thread case and having a radial flange provided with thread guide eyes and a slot to receive the lug on the thread case for maintaining the holder in predetermined angular position on the thread case, a bobbin thread tension on the holder comprising a leaf spring secured to the central portion of the holder with its free end projecting radially therefrom between said guide eyes, a rotatably mounted cam disk on the holder overlying the leaf spring and cooperating indentation and finger means for adjustably retaining the cam disk against rotation on the bobbin holder.
